(57) **CLAIM**

The ornamental design for a golf cart battery with aperture therethrough, as shown and described.

DESCRIPTION

FIG. 1 is a top, side perspective view of the golf cart battery with aperture therethrough;

FIG. 2 is a top plan view of the golf cart battery with aperture therethrough;

FIG. 3 is a bottom plan view of the golf cart battery with aperture therethrough;

FIG. 4 is a left side elevation view of the golf cart battery with aperture therethrough;

FIG. 5 is a right side elevation view of the golf cart battery with aperture therethrough;

FIG. 6 is a rear elevation view of the golf cart battery with aperture therethrough;

FIG. 7 is a front elevation view of the golf cart battery with aperture therethrough; and,

FIG. 8 is a bottom, rear perspective view of the golf cart battery with aperture therethrough.

The broken lines shown in FIGS. 1- 7 are for the purpose of illustrating portions of the golf cart battery with aperture therethrough that form no part of the claimed design.

The broken lines shown in FIG. 8 are for the purpose of illustrating environmental matter and form no part of the claimed design.
